UNITED STATES PATENT OFFICE

CHARLES M. BLANCHARD, OF ELYRIA, OHIO.

VALVE-OPERATING MECHANISM FOR INTERNAL-COMBUSTION ENGINES.

1,124,838.

Specification of Letters Patent. Patented Jan. 12, 1915.

Application filed January 22, 1913. Serial No. 743,450.

To all whom it may concern:

Be it known that I, CHARLES M. BLANCHARD, a citizen of the United States, residing at Elyria, in the county of Lorain and State of Ohio, have invented a certain new and useful Improvement in Valve-Operating Mechanism for Internal-Combustion Engines, of which the following is a full, clear, and exact description, reference being had to the accompanying drawings.

This invention relates to mechanism for operating engine valves, the object being to provide operative mechanism which may be driven by a convenient reciprocating part, but shall open the valve only on alternate reciprocations. Though not limited thereto, the mechanism is particularly well adapted for operating the admission valves of internal combustion engines, especially of the two-cycle type, wherein it is desired to open the valve for each out-stroke of the piston, as, in such type of engine my mechanism may be operated by a reciprocating rod connected directly on an eccentric on the main shaft.

The characteristics of the invention are hereinafter more fully explained and are summarized in the claims.

In the drawing, Figure 1 is a side elevation of an internal combustion engine equipped with my valve mechanism, some of the parts being broken away; Fig. 2 is a vertical section through the cylinder and the admission valve and parts of my operating mechanism, the cam portion of the mechanism being shown in side elevation; Fig. 3 is an edge view of the cam and the roller and arm with which it coacts; Fig. 4 is a development of the arcual face of the cam.

Referring to Figs. 1 and 2, 1 indicates the engine cylinder, and 2 the piston therein, which is connected by a connecting rod and crank (not shown) with the crank shaft 3 (Fig. 1).

4 indicates a bushing mounted in the cylinder wall and having an admission port 5 into the cylinder space, and 6 and 7 are admission passageways for liquid fuel and air under pressure into the bushing. The passageways communicate with spaces formed on the roughened exterior of a plug 8 to thoroughly mix the oil and air.

10 indicates a needle valve adapted to control the opening and closing of the port 5 and thus control the admission of fuel to the cylinder.

The mechanism for operating the valve rod 10 comprises the subject matter of this invention and will be hereinafter more fully described. For the present it should be noted that this rod is connected with a head 11 which rests on a bar 12 carried within a bifurcated operating lever 13 pivoted at 14. The lever is provided with a roller 15 which rests on a cam 20 secured on a rock shaft 21. On the other end of this rock shaft is an arm 22 which is shown as connected by a rod 23 (Fig. 1) with a rock arm 24. This latter arm is on a rock shaft 25, on which a rock arm 26 is connected. The rock arm 26 is shown as connected by a link 27 with the wrist pin 28 of a reciprocating air pump or valve 29. On this same wrist pin is journaled the eccentric rod 30, the strap of which surrounds an eccentric 31 on the main shaft 3.

From the construction described, it results that, for each rotation of the main shaft, the rod 23 is given a complete reciprocation or double-stroke, which rocks the cam 20 back and forth. The stroke of the cam in one direction raises the lever 12 to open the valve, the stroke in the opposite direction being idle, as will be explained. It should be noted that the coupling of the rock arm 26 to the wrist pin of the piston 29 is an incident for simplicity. Any suitable means may be employed for reciprocating the rod 23.

I will now describe the particular construction shown by which the cam operates the admission valve. The head 11, to which the upper end of the needle valve 10 is secured, is slidable in a housing 36 formed in the upper portion of a bracket 37 on top of the main cylinder. Above the head 11 is a compression spring 38, which extends into and is adjusted by the cap 39, which screws downwardly in the housing mentioned. The head 11 is extended downwardly about the rod 10 and rests on the cross bar 12, heretofore referred to, within the lever 13. The pivot 14 of this lever is on the same bracket 37 which carries the housing. The other end of the lever carries between its arm the roller 15, which coacts with the cam. This roller is pressed toward the cam by a spring 41, bearing down on a sliding head 42 in a second housing 43 on the bracket 37, the spring being compressed by a screw plug 45.

It will be understood from the above description that the spring 38 tends to main-

tain the valve 10 on its seat, and does so maintain it, except when lifted by the arm 13. The spring 41 tends to hold the arm with the admission valve closed and the roller 15 pressing on the cam, but when the hump 50 on the cam raises the roller and arm upwardly, such movement raises the admission valve and allows the charge to enter the cylinder.

I accomplish the desired alternate operation of the cam by making the roller 15 laterally shiftable on the pin 51, carried between the two portions of the arm 13, so that the hump 50 on one stroke strikes the roller and on the opposite stroke misses it. I provide two side cams on the cam 20 to effect this shifting of the roller. This is illustrated in Figs. 3 and 4. On either side of the roller 15, are two disks 52 and 53 formed on the roller body and designed to coact with the side cams 54 and 55. These are near the opposite ends of the arcual head and are on opposite sides, as shown. When the cam 54, for example, engages the disk 52 it draws the roller toward the right in Fig. 3, so that it is out of the path of the projection 50 and will be missed by it on the return stroke of the cam. The described shift of the roller draws the disk 53 over against the opposite side of the cam, so that, when the cam edge 55 near the end of this return stroke engages the disk 53 it draws the roller back into position so that it will be engaged on the following stroke, by the pump 50, as shown in Fig. 3.

In the embodiment shown in the drawings, the main eccentric 31 is so set that, as the main piston 2 is about reaching the head position on the return stroke, the cam is moving in a direction from the head of the cylinder toward the crank and thus the hump 50 passes under the roller 15 and raises the admission valve while the piston is at or near the dead center, and holds the valve open during a portion of the outward stroke of the piston. Now, as the cam continues to rock in this direction, the cam edge 54 engaging the disk 52 draws the roller into position to miss the projection 50, and then the eccentric rocks the cam in the opposite direction and carries that projection idly past the roller. As the cam is reaching the limit of its movement in this direction, the edge 55 engages the disk 53 and draws back the roller to normal position so that it is again in the path of the hump 50.

The actual time which the admission valve is open may be regulated with reference to the piston position by turning the rod 23, which has at its ends right and left hand threads 60 and 61 which engage in corresponding sockets connecting with the arms 24 and 22. A suitable knurled hand-hold 62

on the rod 23 furnishes convenient means for turning it, and nuts 63 and 64 lock it.

In order to aid in properly setting the valve, I form on the bracket on which it is mounted a stationary disk-like portion 66 on which I make a suitable mark 67 which is placed so that it is opposite a corresponding mark on the cam when the piston is at the extreme end of the stroke. Now, if it be desired to admit the fuel before the piston arrives at the inner end of the stroke, the rod 23 is turned in a direction to increase its effective length, thus causing the hump to reach the roller sooner than before. On the other hand, to admit the fuel at a later point than the dead center, the rod 23 is turned in the opposite direction.

It will be seen that my valve operating mechanism is simple in construction; is adapted for convenient coupling with any suitable reciprocating part of the engine, and operates to open the admission valve on alternate movements, as desired. The ease with which the time of opening is adjusted is also a feature of the invention.

Having thus described my invention, what I claim is:

1. In an internal combustion engine, the combination of an admission valve, a rock cam member having a projection, an arm connected with the admission valve and having a roller member adapted to ride on the face of the cam, flanges on said roller projecting opposite the sides of said cam member, cam surfaces formed on such sides adapted to engage said flanges whereby one of said members is shifted with relation to the other so that the roller member may avoid the projection on the cam member on one stroke but be engaged by it on the other stroke.

2. The combination of a valve, a cam, a roller adapted to ride on the cam and connected with the valve, a flange on the roller, and a cam projection on the side of the cam mentioned adapted to engage said flange to shift the roller whereby on one stroke the roller may be actuated by said cam and on another stroke may be independent of it.

3. In an internal combustion engine, the combination, with a cylinder and piston, of an admission valve, a roller for operating it adapted to be shifted laterally, a cam having a hump, oppositely inclined edge surfaces, a pair of disks on opposite sides of said roller connected with it and adapted to engage the inclined surfaces respectively, and means for moving said cam, whereby the inclined edges reciprocate the roller back and forth so that the roller is engaged by the hump on one stroke of the cam and not engaged thereby on the opposite stroke.

4. The combination, with a cylinder and piston, of an admission valve, an arm for operating it, a roller carried on said arm

and adapted to be shifted laterally, a rocking cam having a partially cylindrical surface with a hump, oppositely inclined edge surfaces near the opposite ends of the cam, 5 a pair of disks on opposite sides of said roller connecting with it and adapted to engage the inclined surfaces respectively, and means connected with a moving part of the engine for oscillating said cam whereby the 10 inclined edges reciprocate the roller back and forth so that it is engaged on one stroke of the cam by the hump and not engaged thereby on the opposite stroke.

5. In an engine, the combination of a 15 valve, a reciprocating cam, mechanism connecting the valve and cam operative on one stroke of the cam but not on the other, and mechanism for reciprocating the cam, including an intermediate rotatable rod having 20 right and left hand threads connecting it respectively with the cam and driver therefor, whereby the turning of said rod shifts the cam in one direction or the other, changing the relative position of the valve 25 and cam.

6. The combination, of a valve, a rocking cam having a projection, an arm connected with the valve and having a roller adapted to ride on the face of the cam, means for 30 shifting said roller laterally to avoid the projection on one stroke of the cam and be engaged by it on the other stroke, and mechanism for reciprocating the cam, including a rotatable rod having right and left hand 35 threads connecting it with the cam and the operating member therefor respectively, whereby the turning of said rod shifts the cam in one direction or the other.

7. In an engine, the combination, with a cylinder and piston, of an admission valve, 40 an arcual rocking cam, mechanism controlled thereby for opening the valve on one stroke of the cam but not on the other, a stationary disk-like member adjacent to the cam, coöperating indicia on said member 45 and cam, and means for operating the cam and for regulating the position of the effective surface thereof relative to the mechanism operated thereby.

8. In an internal combustion engine, the 50 combination of an admission valve, a reciprocating cam member having an idle portion and an effective portion on one face, an arm connected with the admission valve, a plunger connected with the valve, means acting 55 thereon to seat the valve, an engaging member carried on said arm and adapted to ride said cam, a second plunger and means acting thereon to press the member toward the cam, said member having a surface adapted 60 to be engaged by the effective portion of the cam and having a surface adapted to engage the side of the cam, there being idle and effective surfaces on the sides of the cam adapted to shift one of said members with 65 relation to the other whereby the effective portion engages the corresponding surface on the member on said arm on one stroke but misses it on the other.

In testimony whereof, I hereunto affix my 70 signature in the presence of two witnesses.

CHARLES M. BLANCHARD.
